INVENTOR.
HENRY CHARLEMAGNE
Collier & Pollock, Attorneys

UNITED STATES PATENT OFFICE.

HENRY CHARLEMAGNE, OF BROOKLYN, NEW YORK.

COMBINATION LOCK.

Application filed March 18, 1925, Serial No. 16,328. Renewed April 30, 1928.

This invention relates to improvements in locks, particularly in combination locks, and it is the principal object of the invention to provide a combination lock, the tumblers 5 of which are normally held in their latch-engaging, locking position by means of fingers adapted to be controlled from the combination knobs and dials, and which are disengaged from their latch-engaging position 10 by a special key.

Another object of the invention is the provision of a combination lock of simple and inexpensive construction, yet efficiently and positively operating.

15 A further object of the invention is the provision of a lock of the combination type including a removable key of peculiar configuration, and a latch which is limited in its movements within the lock.

20 A still further object of the invention is the provision of a combination lock allowing, when attached to a door or the like, lateral access to the key for removal and insertion thereof.

25 These and other objects and advantages of my invention will become more fully apparent as the description thereof proceeds, and will then be specifically defined in the appended claims.

30 In the accompanying drawing, forming a material part of this disclosure:

Fig. 1 is a front elevation of a lock constructed according to my invention.

Fig. 2 is a rear elevation thereof after the 35 removal of the housing rear plate looking in the direction of the arrows 2-2 of Fig. 3.

Fig. 3 is a cross-section on line 3-3 of Fig. 2.

Fig. 4 is a longitudinal section on line 40 4-4 of Fig. 2.

Fig. 5 is a fragmentary rear elevation of a modified form of the lock.

Fig. 6 is a cross-section on line 6-6 of Fig. 5.

45 Fig. 7 is a detail side elevation of the lock key.

In this housing 10 three substantially vertical chambers 12, 13 and 14 are formed in which the tumblers 15, 16 and 17 are vertically displaceable within certain limits defined by the rearwardly extending horizontal flanges 18, 19 and 20 respectively.

The casing has also an upper longitudinal slot 21, and a lower longitudinal slot having a 55 depression 22. Within the upper slot 21 is displaceably located a key 23 having a

finger piece 24 and three locking members or wards 25, 26 and 27 respectively adapted to engage under the flanges 18, 19, 20 of the tumblers to hold the same in their upper 60 elevated positions with their lower ends disengaged from the latch 28 slidably arranged within the lower slot and provided with suitable depressions 29, 30, 31 adapted to be engaged by the lower ends of the tumblers, 15, 65 16 and 17, as shown in Fig. 2.

The combination characters are on the flanges of the knobs 32, 33 and 34 on the front plate of the casing, while the said plate carries appropriate marks 35 in the well 70 known manner representing the stopping point when reaching the combination numbers.

The knobs are integral with stub shafts 75 which carry within the casing star wheels 35, 36 and 37 respectively each of which has three short arms or fingers 38 and one longer or operating arm 39 which is adapted upon the proper setting of the combination to engage and bear against the lower rear end of one of the levers 40, 41 or 42 respectively, pivoted intermediate its ends as at 43, 44, 45 in the casing, and having upper gripping fingers or members 46, 47, 48 adapted to grip over the upper face of the 80 flanges 20, 19 and 18 respectively.

85 Springs 49, 50 and 51 are secured at their lower ends to blocks 52, 53 and 54 on the lock frame or body and normally press the levers 40, 41 and 42 towards one direction in which 90 the members 46, 47 and 48 engage or grip over the flanges 20, 19 and 18.

The latch 28 has a pin 55 attached to its lower edge or face adapted to slide in depression 22 and to limit the movements of 95 the latch or locking bolt 28.

The device operates as follows:

Assuming the lock is in its unlocked position, and the flanges 18, 19 and 20 of the tumblers rest upon the wards 25, 26 and 27 100 of key 23 within the slot 21. If this key is now laterally removed, the tumblers will fall down and their lower ends will engage the depressions 29, 30, and 31 of the latch 28 which in this position is pushed inwardly 105 until its pin 55 engages the rear end of depression 22, and the lock will be effectively locked by the proper manipulation of the combination to bring the gripping elements of the locking fingers 40, 41 and 42 into engagement over the flanges 20, 19 110 and 18.

If it is now desired to open the lock, the combination is properly operated to disengage the gripping members from the tumbler flanges, successively, and when the key 5 is again inserted into slot 21, and thereafter bodily raised, it will raise the tumblers out of engagement with the depressions of the latch bolt and rest with their flanges again upon the wards of the key.

10 In the modified form of my invention illustrated in Figs. 5 and 6, the lock is provided with an auxiliary knob 57 on a stub shaft 58 having its rear end located in the chamber 59 of the lock casing and which 15 carries therein a pinion 60 in mesh with a rack bar 61 upon the longitudinal displacement of stub shaft 58, said rack bar 61 being guided in suitable guides 62, and 63 respectively and connected at its upper end 20 to a horizontally arranged arm 64 adapted to bear from below against the lower face of a key bar 65 carrying the tumblers 65, 66, 67 and 68 having upper flanges 69, 70, 71 and 72 respectively adapted for engagement by 25 the gripping members of the locking fingers as in the preferred form.

It will be clear that a lowering of the key bar 65 by the proper manipulation of the knob 57 and the rack bar thereby, will bring 30 the tumblers into engagement with the depressions in the latch bolt, as in the preferred form, while an elevation of the rack by the proper manipulation of the knob 57 after the disengagement of the gripping 35 members from the tumbler flanges, upon the proper setting of the combination, will lift the tumblers out of engagement with the depressions of the lock bolt, and will allow an opening of the locked door.

40 Changes such as fall within the scope of the appended claims may be made in the construction of the details of my improved lock without departure from the spirit of my invention.

45 Having thus described my invention what I claim as new and desire to protect by Letters Patent of the United States is as follows:—

50 1. A combination lock comprising a recessed locking bolt, a plurality of tumblers

having upper rearwardly extending flanges adapted to engage with their lower ends the recesses in said locking bolt, spring controlled means for locking said tumblers in their engaged position with said locking bolt, allowing a disengagement therefrom upon the proper manipulation of the combination, and a key for operating said tumblers to raise and lower the same after their disengagement by said spring controlled 60 locking means, an auxiliary knob, a spindle therefor ending in a chamber of the lock casing, a gear on said spindle within said chamber, a rack in mesh with said gear adapted to be raised and lowered by the 65 operation of said knob, and guides for said rack, said rack adapted to engage said key to raise and lower said tumblers.

2. In a combination lock of the class described, a recessed locking bolt, a plurality 70 of tumblers adapted to engage the recesses of said bolt, a key for raising and lowering said tumblers, means for locking the same in their respective positions, a plate for engaging said key to lift and lower the 75 same, and a rack bar to which said plate is attached, means for raising and lowering said rack bar and plate, and a pinion adapted to be operated by a knob for operating said rack bar.

80 3. The combination in a combination lock having special key supporting tumblers in their position disengaged from the latch, allowing a falling of said tumblers into the latch recesses to lock the lock, of a recessed 85 sliding latch, means for limiting the movements of said latch in either direction, a plurality of tumblers having upper flanges, adapted to engage with their lower ends into the recesses of said latch, a plurality of 90 locking fingers pivoted intermediate their ends, gripping members on said fingers adapted to engage over the flanges of said tumblers, means for normally pressing said members into engagement with said fingers, 95 and combination controlled means for disengaging said members from said flanges.

In testimony whereof I have affixed my signature.

HENRY CHARLEMAGNE.
